UNITED STATES PATENT OFFICE.

EVERETT R. BURTNETT, OF LOS ANGELES, CALIFORNIA, ASSIGNOR OF ONE-HALF TO
CHARLES A. BURTNETT, OF LOS ANGELES, CALIFORNIA.

INTERNAL-COMBUSTION ENGINE.

Application filed November 20, 1922. Serial No. 602,180.

To all whom it may concern:

Be it known that I, EVERETT R. BURTNETT, a citizen of the United States, residing at Los Angeles, in the county of Los Angeles, State of California, have invented new and useful Improvements in Internal-Combustion Engines, of which the following is a specification.

My invention relates to internal combustion engines and has for its principal object the provision of a relatively simple practical structure that embodies features in keeping with the present and future demands, as evidenced by the trend of present design in internal combustion engines, and likewise in keeping with the recently discussed and accepted ideas of those most advanced in the art to which my invention relates.

A low cost motor vehicle must have a relatively short wheel base, and to afford ample room in the tonneau for the passengers, the engine for operating such a vehicle must of necessity be relatively short.

Engines having a V-arrangement of cylinders are much shorter, for a given number of cylinders of given bore and stroke than the engines having their cylinders arranged in a row.

Owing to the variation in time periods between power impulses where four cylinders operating on the four stroke cycle is contemplated, the V-arrangement is not practical.

Two cylinders in line, 180 degrees apart, or four in a row provides the only uniform operating arrangement for a four cylinder engine unit that operates on the four stroke cycle.

The only practical adaptation of the twin cylinder 180 degree arrangement, would be horizontal but the overall width of the engine prohibits this arrangement on account of the desire to maintain a maximum turning range for the front wheels.

Therefore, the four cylinder, four cycle engine stands as a "vertical row" type, and in such an engine there are only two power strokes per revolution of the crank shaft.

There is a period between the near end of one power stroke and before the beginning of the succeeding stroke, where there is no driving effort at all, such condition arising

by reason of the fact that the exhaust valve opens before the piston on its expansion or power stroke reaches out dead center.

Such action develops torque variation, which is the greatest influence in the adaptation of the six cylinder "in row" arrangement, wherein a power lap or constant driving effort is provided. However in this type of engine, the length of the six cylinders in a row practically prohibits its general adoption and use in cars of minimum production cost.

Further, there is found in six cylinder engines, a certain degree of torque variation, and which is due to the great degree of expansion produced by the piston completing a power impulse stroke before a second expansion period begins.

It is therefore desirable to provide a construction that will develop more constant torque and at the same time minimize the overall length of the engine, or, in other words, to produce a simplified construction that will produce the effect of an eight cylinder V-arrangement four cycle engine.

It will be understood that practically all conventional engines operating on the four stroke cycle principle, by necessity of function, employ two valves per cylinder, and each valve must have a separate cam and complete valve actuating mechanism including a spring pin, cam follower, rocker arm and so forth.

Four cycle operation necessitates the driving of the cam shaft at one-half engine or main crank shaft rotative speed and likewise necessitates the use of timing gears, and separate bearings for the cam shaft.

An eight cylinder four cycle engine has sixteen valves and their actuating mechanisms including timing gears and cam shaft, results in an engine of many parts and prohibits its adaptation to a low cost motor vehicle.

Therefore it is one of the objects of my invention to provide an engine having a block of V-formation which will produce the equivalent in power impulses to the four cycle eight cylinder engine and at the same time to greatly simplify the construction and manufacturing costs, eliminate valves,

timing gears, or auxiliary valve actuating shafts and consequently enabling the improved structure to be utilized as a power unit in motor vehicles of relatively low cost.

- 5 Further objects of my invention are to provide an engine having the desired torque, driving smoothness, mechanical balance, silence of operation and reliability resulting from extreme simplicity.
- 10 At low engine speed, and at a time when a maximum power output is desired, the piston of the conventional engine will be found to be very close to dead center, and at this time, the greatest internal pressure is
- 15 produced as a result of combustion following the ignition of a full volume charge allowed by full throttle and long cylinder filling time duration, due to the low engine speed while laboring under heavy load.
- 20 Under such conditions the crank of the shaft is still in dead center toggle and it is rigidly resisting the internal pressure and suffering mechanical hardship through the bearing line. Further, this condition materially increases the time period of maximum charge temperature duration of exposure to the externally cooled cylinder wall by the retardation of immediate expansion in power development, and brings about a drop
- 25 in pressure due to heat loss by radiation.
- 30 Therefore it is one of the objects of my invention to provide an engine having a second piston to the combustion chamber and to connect said second piston to the crank
- 35 to which the primary power piston is connected but with compound angular leverage on said crank and offset to the axis of said crank while in dead center line with the primary power piston and which arrangement permits the immediate angular driving effect to the crank, in the direction of rotation and consequently increasing the power development by greater conversion of reciprocatory motion to rotary motion.
- 40
- 45 The quality of the liquid hydrocarbon at present utilized as fuel in internal combustion engines, is such that a considerable degree of heat is required to properly vaporize the fuel charge, and to attain highest efficiency and insure complete combustion of all the molecules of the charge, the latter should be thoroughly dry. Where this last mentioned condition exists, the condensation of the charge in the combustion chamber is
- 50 eliminated and, in this connection, it will be understood that condensation of the fuel charge is destructive to the oil film around the piston and dilution of the lubricating oil volume occurs.
- 55
- 60 In a conventional engine of a given piston displacement, operating on a four stroke cycle and inducting a fuel charge by suction, from within and direct to the combustion chamber, a reduction in power range is the
- 65 result of a set system of heat application

to the fuel vaporization and manifold system.

As a result of external expansion of the ingoing charge, the admission of a volume of less air value when the engine is operating at low speed, results in the increase of the time period duration of the inflowing charge through the preheated vaporization system, and the volume of less air value, necessitates the reduction of molecular density of the charge and reduces combustion pressure and expansion force.

Therefore it is a further object of my invention to provide an engine having a combustion cylinder surrounded by a water cell for cooling purposes, to provide a precompressing or fuel charge pumping cylinder having greater piston displacement than the combustion chamber and having an exhaust gas cell surrounding it, in order to preheat the gaseous mixture charge pumped through it, and the overcapacity of the pump cylinder providing the range and forcing the induction of the superheated gaseous mixture charge to the combustion chamber.

The conventional engine operating on the four stroke cycle principle has a compression clearance content fixed by the designer, and which is of a certain ratio to the cubic content of the piston displacement, thus providing a given compression pressure when the cylinder is permitted to fill the displacement content. The conventional principle of engine control and operation, is, to throttle the engine by strangulation of the combustion cylinder of initial volume, said throttling being effected by valvular means in the inlet manifold and operating to vary the volume of the admitted charge.

Hence the maximum compression as intended by the designer is only obtained when the engine is allowed full throttle, the compression at all times being in ratio to the initial volume admitted.

It is a recognized and accepted fact that thermal efficiency and power obtained from a given quantity of fuel, increases as does the compression and since approximately ninety per cent of the time, the average motor vehicle is operated with about one-quarter throttle, then the compression must be only about twenty-five per cent efficient.

Thus, further objects of my invention are to provide an internal combustion engine, operating on the two stroke cycle principle, wherein the initial volume is constant, the scavenging of atmospheric pressure residue from the combustion chamber being in ratio to the inducted gaseous mixture, to provide a charge of two parts, stratified in volume by the form of the combustion chamber and the positions of inlet and exhaust with respect to each other, so that

there will be no loss of the fresh charge with the residual products of combustion expelled and so that, with a minimum charge inducted in volume, in ratio to the volume of residual gases remaining in the cylinder, dilution will not occur and combustion of the minimum gaseous charge will be flexible, regular and complete at any throttle, and the throttling being accomplished by 10 the volume control of the initial charge admitted to the pumping cylinder.

In view of the fact that in all two stroke cycle engines, some means must be provided for precompressing the gaseous charge to 15 force induction into the combustion chamber that is occupied by burned products of combustion, it is one of the objects of my invention to provide, in an engine of the character described, a pumping cylinder for 20 each combustion cylinder, the connecting rod of each pumping cylinder being attached to the same crank as the connecting rod of one of the combustion cylinder pistons, each pumping cylinder and adjacent 25 combustion cylinder being arranged in V-form, thereby causing the pistons of the respective cylinders to reach dead centers at different times.

My invention contemplates a structure 30 wherein the crank of a pumping cylinder is effective in compressing a charge for a combustion cylinder having a crank throw opposite in crank position to the crank of the combustion cylinder to which it also, 35 is connected thereby providing a maximum compression after the piston of the combustion chamber to which it supplies a charge, has passed the lower or crank end dead center and beginning the compression 40 stroke so that a maximum volume transfer of a new charge will be effected.

With the foregoing and other objects in view, my invention consists in certain novel features of construction and arrangement 45 of parts that will be hereinafter more fully described and claimed and illustrated in the accompanying drawings, in which:—

Fig. 1 is a vertical section taken transversely through an engine of my improved 50 construction.

Fig. 2 is a section, on a reduced scale taken on the line 2—2 of Fig. 1.

Fig. 3 is a detail section taken on the 55 line 3—3 of Fig. 1.

Referring by numerals to the accompanying drawings which illustrate a practical embodiment of my invention, 10 designates a V-shaped cylinder block, in one leg or side of which is formed a series of combustion chambers 11, and a corresponding series of auxiliary or secondary combustion chambers 12.

The respective series of chambers 11 and 12 are arranged in rows and with the members of the inner row or series of second-

ary chambers 12 being paired with the members of the series of combustion chambers 11.

The axes of the chambers 11 and 12 are preferably parallel and the upper ends of 70 the members of each pair of chambers are in direct communication with each other by means of a pocket or recess 13 that is formed in the under side of a head block 14, and which latter provides a closure for the upper ends of all of the cylinders.

This pocket 13 performs the functions of an ignition chamber.

Formed in the other leg or side of the V-shaped block 10 is a series of gaseous 30 fuel compression chambers 15, the members of which are preferably disposed directly opposite to the members in the rows of combustion chambers 11 and 12.

Block 10 is provided with a skirt member 35 16 that is positioned upon and combines with a box-like structure 17 in forming a crank case and arranged in the end walls thereof are suitable bearings for a crank shaft 18.

Arranged for reciprocatory movement within each combustion chamber 11 is a power piston 19 that is connected by the usual connecting rod 20 to the corresponding crank on shaft 18.

Arranged for reciprocatory movement within each compression chamber 15 is a compression piston 21 that is connected to the corresponding crank of shaft 18 by connecting rod 22.

In order that both connecting rods 20 and 22 may be connected to the same crank, it is necessary to bifurcate the lower end of crank 22 and which construction is clearly illustrated in Fig. 3.

Arranged for reciprocatory movement within each chamber 12 is a piston 23 and connecting the wrist pin thereof to a wrist pin 24 that is mounted in a yoke 25 in the lower portion of rod 22 is a connecting 110 rod 25^a.

As illustrated in Fig. 1, compression chamber 15 is somewhat larger in diameter than combustion chamber 11, and likewise the latter is somewhat larger in diameter 115 than its companion chamber 12.

The upper end of each compression chamber is connected to the intermediate portion of the auxiliary chamber 12 of the next adjacent set of transversely aligned chambers by the transfer duct 26, and this construction necessitates a cross over arrangement of the ducts as clearly illustrated in Fig. 2. These transfer ducts are formed in a web or block 27 that is disposed between the upper portions of the legs of block 10 and formed in said web and surrounding said ducts are communicating chambers 28 through which may pass exhaust gases or products of combustion.

By virtue of the cross over arrangement of the transfer ducts, each compression piston compresses gaseous fuel for the primary and secondary combustion chambers of the next adjacent set of transversely aligned chambers.

Formed on the side of the leg of block 10, in which the compression chambers 15 are formed, is a horizontally disposed rib 29 in 10 which is formed a gaseous fuel inlet duct or manifold 30.

The wall surrounding this duct is provided with a chamber 31 that communicates with the chambers 28 and leading from the 15 duct 30 to gaseous fuel inlet ports 32, that are located at an intermediate point in the wall of each chamber 15, are branch ducts, such as 33.

Inlet ports 32 are positioned so as to be 20 wholly uncovered when compression piston is at the lower or inner end of its stroke.

Leading to duct or manifold 30 from a suitable source of supply, preferably a carburetor is a gaseous fuel supply pipe 34.

25 The upper ends of all of the compression chambers are closed by a head block 35 in which is formed a chamber 36 through which, heated products of combustion or the like may be circulated.

30 Formed in head block 14 and in the walls surrounding chambers 11 and 12 are chambers 37, through which may be circulated suitable cooling fluid, such as water.

Seated in head block 14, directly above 35 each chamber 12 is a spark plug 38, and the inner ends of the electrodes thereof project into the ignition chamber 13.

The ends of the transfer ducts 26 enter 40 the secondary chambers 12 at points where the openings or ports will be wholly uncovered when the pistons 23 are at the lower or inner ends of their strokes.

Formed through the wall of block 10 that surrounds each combustion chamber 11 and 45 at a point where it will be wholly uncovered when piston 19 is at the inner end of its stroke is an exhaust port 39 and leading therefrom to a point in chamber 28, immediately adjacent to the crossing point of 50 the transfer ducts 26 is an exhaust duct 40.

By virtue of this arrangement, the highly heated products of combustion from the chambers 11 are led directly to the chamber 28 and directed against the walls surrounding the transfer ducts 26, thereby pre-heating the gaseous fuel immediately before its entry into the chamber 12.

The operation of my improved engine is as follows: As pistons 19 and 23 pass their 60 high centers, the compressed charge of gaseous fuel within chamber 13 is ignited by a spark produced between the terminals of the electrodes of plug 38 and the pressure of expansion following combustion is directed 65 against the heads of said pistons 19 and 23

to move the same downward on the power stroke.

The pressure upon piston 19 is transmitted directly to crank shaft 18 through rod 20 while the pressure upon piston 23 70 is, by a compound leverage action transmitted to the crank shaft through rods 25^a and 22.

Thus a powerful driving torque is transmitted to the crank shaft on each downward 75 movement of the pistons 19 and 23.

Inasmuch as rod 20 is directly connected to the crank shaft 18, piston 19 will travel further and at greater speed than piston 23, and when said piston 19 approaches the 80 lower end of its stroke, exhaust port 39 will be uncovered, thereby permitting the pressure within chambers 11, 12 and 13 to drop to atmospheric pressure and the hot exhaust gases, as hereinbefore stated are led 85 through duct 40 to heat the gaseous fuel during its passage through transfer ducts 26.

Immediately succeeding this opening of the exhaust port piston 23 reaches low center, thereby uncovering the inner end of the 90 transfer duct 26 and a charge of gaseous fuel that was compressed during the upward travel of the piston 21 in the next adjacent transverse set or row of cylinders will enter chambers 12.

It will be understood that the cranks on shaft 18 are arranged approximately 180 degrees apart, so that as one set of pistons 19 and 23 travel downward on the power stroke as just described, the compression 100 piston of the next adjacent transverse set of cylinders is moving upwardly to compress a charge of gaseous fuel in the upper portion of chamber 15 and which compressed charge passes through the corresponding transfer duct 26 and into the 105 chamber 12 as just described.

On the succeeding upward travel of pistons 19 and 23, the admitted charge of compressed preheated gaseous fuel and the 110 residual products of combustion, will be compressed within ignition chamber 13 and the total charge volume will be stratified, inasmuch as practically the entire volume of gaseous fuel admitted will be compressed 115 in chamber 13 directly above chamber 12, and with the residual products of combustion compressed in that portion of chamber 13, directly above chamber 11.

Gaseous fuel is admitted to compression 120 chamber 15 through ports 32 and which latter are uncovered when piston 21 reaches the lower end of its travel.

Thus it will be seen that I have produced a two stroke cycle internal combustion engine 125 that embodies the following desirable features viz, simplicity of structure, relatively few parts and of minimum overall length, thereby permitting it to be used as the power plant in low cost vehicles, maxi- 130

mum power as a result of the compound expansive leverage action on the crank shaft, the super-heating and pre-compression of the gaseous fuel, the stratification of the 5 charge when compressed within the ignition chamber, absence of valves and their actuating parts and mechanisms, absence of timing gears, and silence of operation.

It will be understood that minor changes 10 in the size, form and construction of the various parts of my improved engine may be made and substituted for those herein shown and described without departing from the spirit of my invention, the scope 15 of which is set forth in the appended claims.

I claim as my invention:

1. An internal combustion engine having a pair of connected combustion chambers and a gaseous fuel precompression chamber, 20 there being a passageway from said precompression chamber to one of the combustion chambers, pistons arranged for operation within all of said chambers, a crank shaft, the piston of one of the combustion chambers 25 and the piston of the precompression chamber being connected to one of the cranks of said crank shaft and a connection between the other one of the combustion chamber pistons and the connection between 30 the piston of the precompression chamber and said crank shaft.

2. An internal combustion engine having a pair of connected combustion chambers and a gaseous fuel precompression chamber, 35 there being a passageway from said precompression chamber to one of the combustion chambers, a crank shaft, the piston of one of the combustion chambers and the piston of the precompression chamber being connected to one of the cranks of said crank shaft, a connection between the other one 40 of the combustion chamber pistons and the connection between the piston of the precompression chamber and said crank shaft, means for admitting gaseous fuel to the precompression chamber and one of the combustion chambers being provided with an exhaust port.

3. An internal combustion engine having 50 a pair of connected combustion chambers and a gaseous fuel precompression chamber, there being a passageway from said precompression chamber to one of the combustion chambers, a crank shaft, the piston of one 55 of the combustion chambers and the piston of the precompression chamber connected to one of the cranks of said crank shaft, a connection between the other one of the combustion chamber pistons and the connection be- 60 tween the piston of the precompression chamber and said crank shaft, means for admitting gaseous fuel to the precompression chamber, one of the combustion chambers being provided with an exhaust port 65 and means for utilizing the exhaust from the

combustion chambers for heating the pre-compressed gaseous fuel prior to its entry into said combustion chambers.

4. An internal combustion engine having primary and secondary expansion chambers 70 and a gaseous fuel precompression chamber, an ignition chamber connecting said primary and secondary expansion chambers, pistons arranged for operation within said expansion and precompression chambers, a crank shaft, a rod connecting the piston of the primary expansion chamber to a crank on said crank shaft, a rod connecting the piston of the precompression chamber to said crank and a rod connecting the piston 75 of the secondary expansion chamber to said last mentioned rod.

5. An internal combustion engine having primary and secondary expansion chambers 80 and a gaseous fuel precompression chamber, an ignition chamber connecting the expansion chambers, pistons arranged for operation within said expansion and precompression chambers, a crank shaft, a rod connecting the piston of the primary expansion chamber to a crank on said crank shaft, a rod connecting the piston of the precompression chamber to said crank, a rod connecting the piston of the secondary expansion chamber to said last mentioned rod, means for admitting gaseous fuel into the precompression chamber, and the primary expansion chamber being provided with an exhaust port.

6. An internal combustion engine having primary and secondary expansion chambers 90 and a gaseous fuel precompression chamber, an ignition chamber connecting the expansion chambers, pistons arranged for operation within said expansion and precompression chambers, a crank shaft, a rod connecting the piston of the primary expansion chamber with said crank shaft, a rod connecting the piston of the precompression chamber to said crank, a rod connecting the piston of the secondary expansion chamber to said last mentioned rod, means for admitting gaseous fuel into the precompression chamber, the primary expansion chamber being provided with an exhaust port, 100 and means for utilizing the exhaust from the expansion chambers for heating the pre-compressed gaseous fuel prior to its entry into said combustion chambers.

7. An internal combustion engine having 110 a pair of chambers connected at one end to form a single clearance space wherein compression, combustion and expansion take place, the axes of said connected chambers being substantially parallel, said engine also having a gaseous fuel precompression chamber, the axis of which, is disposed at an angle with relation to the axes of the connected chambers, pistons arranged for operation within said connected chambers and the precompression chamber, a crank shaft to 120 125 130

which said pistons are connected and the axes of all of the cylinders occupying a plane that is substantially at right angles to the axis of the crank shaft, the piston of one of the first mentioned connected chambers and the piston of the precompression chamber being connected to one of the cranks of said crank shaft, and a connection

between the piston of the other one of said connected chambers and the connection between the piston of the precompression chamber and the crank of the crank shaft. 10

In testimony whereof I have signed my name to this specification.

EVERETT R. BURTNETT.
